L. E. SALISBURY.
 TEXTILE LOOM SHUTTLE OF THE NON-RECIPROCATING TYPE.
 APPLICATION FILED APR. 30, 1915.
1,170,679. Patented Feb. 8, 1916.

UNITED STATES PATENT OFFICE.

LEVI E. SALISBURY, OF PROVIDENCE, RHODE ISLAND.

TEXTILE-LOOM SHUTTLE OF THE NON-RECIPROCATING TYPE.

1,170,679.

Specification of Letters Patent.

Patented Feb. 8, 1916.

Original application filed October 16, 1913, Serial No. 795,492. Divided and this application filed April 30, 1915. Serial No. 24,912.

To all whom it may concern:

Be it known that I, LEVI E. SALISBURY, a citizen of the United States, residing at Providence, in the county of Providence and State of Rhode Island, have invented 5 certain new and useful Improvements in Textile-Loom Shuttles of the Non-Reciprocating Type, of which the following is a specification.

10 In a divisional pending application for patent filed by me in the United States Patent Office, I have described and claimed certain novel devices adapted for use in textile looms of the automatic multiple-shuttle 15 type; an example of which loom was patented to me on the 10th day of February, 1903, No. 720,181.

The subject of the present application, 20 which is divided from said pending application, relates more particularly to an improved construction of the shuttle of such automatic multiple-shuttle loom.

The essential object of the present device 25 is to produce a comparatively short shuttle devised to receive a much greater length of infolded pick or weft-thread; it being borne in mind that the shuttle moves continuously in one direction, or non-reciprocatorily, and is adapted to take in and deliver therefrom 30 thread or yarn sufficient for one pick only; each shuttle of the series employed being newly charged automatically with a length of weft-yarn as it passes the shuttle-charging station.

35 By means of the improvement the loom is enabled to use a greater number of weaving units without increasing the length of the shuttle-propelling chain, or even the length of the loom itself, thereby correspondingly increasing the amount of output 40 or fabric without increasing the normal rate of speed, and obviously decreasing the cost of fabric production.

In the accompanying drawings illustrating 45 my improved shuttle, Figure 1 represents a top plan view, a portion of the upper plate broken away, showing the moving shuttle in the act of being normally charged with weft-yarn; Fig. 2 is a similar plan view, showing the weft being normally withdrawn from the rear end of the traveling shuttle; Fig. 3 represents a transverse section, taken on the irregular line 3—3 of Fig. 1; Fig. 4 is a side elevation, partly in 50 section, of one of the shuttle-fingers; Fig.

5 is a front side or edge view of the shuttle, in reduced scale; and Fig. 6 represents, diagrammatically, in outline, how the yarn is disposed or folded on the shuttle-fingers, and also showing the yarn being withdrawn. 60

The following is a more detailed description of my improved shuttle: A designates the shuttle as a whole, arranged to be mounted and propelled in any suitable manner, as, for example, substantially as represented in my said Patent No. 720,181 before referred to. Each shuttle is provided with main upper and lower flat plates s^1 , s^2 , respectively, having guide-flanges s^3 on the back edge thereof. The upper plate s^1 has a narrow, open longitudinal central slot s^8 therethrough, arranged to freely receive singly the apertured outer ends c^2 of a plurality of suitably actuated weft-positioning arms c^1 , through which the weft-yarn is drawn and infolded into the traveling shuttles in a manner analogous to that employed in my said patented loom. To the rear end of the shuttle is mounted a small revoluble wheel s^5 , adapted to frictionally engage a member (not shown) of the shuttle-propelling mechanism. To each of the outer longitudinal edges of the shuttle frame or body is pivoted on pins n^3 a row of uniformly spaced swinging light shuttle-fingers N ; the said pivots n^3 of one row alternating with the pivots of the other or opposite row. 70 75 80 85

The shuttle-fingers or units are substantially duplicates of one another and are adapted to swing on the respective pivot-pins alternately in a successive order from one side to the other in a horizontal plane. In order to prevent the shuttle-fingers from moving too freely, the heel portion of each 90 member N may be provided on its upper side or face with a recess n^2 in which is confined a light coil-spring n^4 capped by a disk n^5 of felt or other suitable material arranged to press against the underside of the upper plate s^1 of the shuttle; the device being employed as a friction-brake in that it forms a slight drag or resistance. See Fig. 4. 95 100

The free end portion of each shuttle-finger N , remote from its pivot pin n^3 , is provided with a pair of short, downwardly extending pins n which are fixed to the finger and swing bodily with it; these pins n are caused to engage the weft-yarn w^1 at the two points and fold it into two connected 105 110

elongated loops, more fully described later. To the inner upper face of the base-plate s^2 are secured two parallel longitudinal rows of upwardly extending, relatively stationary, uniformly spaced studs s^{10} , each row being equi-distant transversely from the longitudinal center line $y-y$ of the shuttle, the studs s^{10} of one row alternating with those of the other row in a zig-zag manner.

5 As thus arranged, the longitudinal center line z of the respective shuttle-finger units passes through the centers of the pins n^3 and n , n . When the fingers are closed or folded the central line z of each finger will lie between a pair of the contiguous studs s^{10} and at right angles to the center line $y-y$ of the shuttle itself. See Fig. 6. Fig. 1 represents the position of the fingers N , etc., at the commencement of charging the shuttle with the weft w^1 , and Fig. 2 shows the continuously looped or infolded weft being withdrawn at the rear end of the shuttle from the fingers as the latter swing outward successively on their pivots n^3 about 60° .

10 25 In charging the shuttle with yarn w^1 the two pins n , n , of each pivoted finger N cooperate with a corresponding pair of the stationary studs s^{10} in the multiple-folding of the yarn; for example, referring to Fig. 1, the downwardly extending spaced outer pins n^x , n^x of the yarn-threaded finger N^x are carried by the latter in its arcuate movement from the normally open or empty position to the fully closed position shown, transversely of the shuttle. The finger in its initial movement causes the pair of pins n^x , n^x thereof to swing past the two diagonal or staggered studs s^x , s^x , whereby the yarn already bent around said pins n^x is caused 30 to slidably engage the studs s^x and form the two elongated double-loops m^x , the live end portion of the yarn being immediately engaged by the pins of the next alternate finger and studs to produce other double loops, 35 and so on, successively, until the shuttle is fully charged with the weft. As thus devised, each finger takes up or infolds practically four times its net length of weft. It may be stated that the elements designated 40 in Fig. 1, N^x , n^x , and s^x , are the same as the corresponding members indicated by N , n , and s^{10} , respectively.

45 In actual operation under normal conditions the pick or weft-charged shuttle is supposed to be moving horizontally between the upper and lower sections of shedded warps, the rear end of the length of weft-yarn being in the initial warp-section before the weft is severed from its spool or supply; 50 the drag or retarding tension effect upon the weft of the traveling shuttle at the same time causing the weft to be withdrawn or unfolded from the swinging fingers without entanglement, and to lie substantially true 55 and straight while it is being progressively 60 65

beaten up into the web. Means for laying the weft between the warps are not represented, since they are not claimed in this application. Mechanism of this general character is, however, illustrated in my said Patent No. 720,181, to which reference can be made if desired.

70 By means of my improvement the traveling shuttle is adapted to be accurately self-threaded or charged with the yarn by the successive action of the pivoted fingers N in coöperation with the relatively stationary studs s^{10} ; the construction also permits the yarn to render freely while it is being withdrawn from the shuttle. It will be observed 75 that it is practically impossible for the yarn to become fouled or entangled while the shuttle is being charged, or even while the yarn is being drawn from it. The forward finger of the series is or may be provided 80 with a short pin s^6 extending through a curved slot s^7 of the upper plate s^1 of the shuttle; the said pin s^6 being adapted to engage and actuate a member of a suitable weft stop-motion device in case the shuttle 85 has failed to properly deliver its weft into the web. A device of this character was patented to me April 19, 1910, No. 955,212.

I claim as my invention:—

1. In a shuttle of the general character 90 described, a flat, hollow frame or body having spaced apart connected upper and lower parallel plate members, a longitudinal row of uniformly spaced inner stud members arranged between the plates in a staggered or 95 zigzag manner relatively to the median line of the shuttle, said stud members being rigidly secured to the lower plate and extending upwardly therefrom at right angles to it, and a series of swinging thin pin-carrying 100 finger members inclosed in the shuttle and pivoted respectively in front and back edge rows of the frame, the fingers of one row alternating with the fingers of the other 105 row, and having the outer or free end portions of the fingers adapted to swing freely across the upper ends of the corresponding 110 studs, substantially as described.

2. In a shuttle of the type described, having a hollow frame or body provided internally with a row of fixed studs s^{10} arranged in a staggered or zigzag manner with relation to the longitudinal center line of the shuttle, a row of yarn-infolding fingers N pivoted in one edge of the shuttle, a row of similar fingers pivoted in the opposite edge, the fingers of one row alternating with those of the other row, and having the arm portion of each of said fingers provided with one or more downwardly extending pins n arranged with respect to the said studs, for the purpose set forth.

3. In a shuttle of the character described, the combination of a hollow body or frame, a plurality of fingers adapted to infold a

length of yarn, said fingers being pivoted longitudinally within the frame in laterally separated outer parallel rows, the fingers alternating with one another and provided 5 respectively with a pair of depending pins movable therewith for looping the yarn, and relatively stationary upwardly extending studs having their centers arranged in a longitudinal direction in a zigzag manner with 10 respect to the median line of the shuttle, whereby in charging the shuttle with yarn,

the pins *n* of a finger are adapted to co-operate with certain of the fixed studs and infold a length of yarn exceeding the net length of the finger member a plural or 15 multiple-fold.

In testimony whereof I have affixed my signature in presence of two witnesses.

LEVI E. SALISBURY.
